DES 551
4-19-1853

Fig. 1.

Des. 551

Charles Chinnock, of New York, N.Y.

Letters Patent No. 551 Dated Apr. 19th 1853.

.....

The schedule referred to in these Letters Patent and making part of the same

.....

To all whom it may concern:

Be it known that I, Charles Chinnock, of the City, County, and State of New York, have invented or produced a new and original design for Cast metal fronts of Clock Cases; and I do hereby declare, that the following is a full, clear, and exact description of the same reference being had to the accompanying drawings forming part of this specification, in which

Fig: 1, is a front view.

Fig: 2, a side view.

Fig: 3, a vertical section through the centre.

Fig: 4, a horizontal section in the line, a, a, of Fig: 1.

Fig: 5, a horizontal section in the line b, b.

Fig: 6, a horizontal section in the line, c, c.

Fig: 7, a horizontal section in the line, d, d.

Similar letters of reference indicate the same parts in all the Figs.

The front which forms the subject of this design, is for a case which is to be suspended, and therefore it has no base. It consists of a single plate of metal, cast as thin as is consistent with a view to proper strength. The centre part surrounding the dial opening is flat and is surrounded by raised ornamentation having the appearance of a frame. The precise form of the ornament is shown very accurately in the drawings and will be better understood by them than by any description, further than that the most prominent features are lettered to enable their form to be traced by comparing them in the different Figs. The plate may be ornamented in a variety of ways to suit various tastes.

What I claim as my invention and desire to secure by Letters Patent, is

The design and configuration of the metal plate represented fully in the drawings which are herein explained, the same form

3

ing the front of a clock case.
